MIXER FOR LIQUIDS OR THE LIKE

John J. Hughes, Jr., 3027 N. Marietta Ave.,
Milwaukee, Wis. 53211

Original design application June 23, 1969, Ser. No. 17,809,
now Patent No. 218,853, dated Sept. 29, 1970. Divided
and this application Apr. 28, 1970, Ser. No. 22,692

Term of patent 14 years

Int. Cl. D15—05

U.S. Cl. D55—1

FIG. 1

FIG. 2

FIG. 3

FIG. 4

FIG. 1 is a side elevation of a mixer for liquids or the like embodying my new design;

FIG. 2 is a front elevation thereof;

FIG. 3 is a rear elevation thereof; and

FIG. 4 is a top plan view thereof.

This application is a divisional of parent application, Ser. No. D. 17,809, filed June 23, 1969, and entitled Mixer for Liquids or the Like, now Pat. No. D. 218,853.

The coupling guard and the electric motor shown in broken lines are for illustrative purposes only.

I claim:

The ornamental design for a mixer for liquids or the like, substantially as shown and described.
